UNITED STATES PATENT OFFICE.

JOSEPH E. FAZAKERLEY, OF PITTSFIELD, MASSACHUSETTS.

HOSPITAL BED.

Application filed May 5, 1924. Serial No. 711,226.

To all whom it may concern:

Be it known that I, JOSEPH E. FAZAKERLEY, a citizen of the United States, residing at Pittsfield, in the county of Berkshire and State of Massachusetts, have invented certain new and useful Improvements in Hospital Beds; and I do declare the following to be a full, clear, and exact description of the invention, such as will enable others skilled in the art to which it appertains to make and use the same.

My invention relates to improvements in hospital beds of the type in which the mattress support is provided with a pair of transverse separable sections, and means are provided for elevating a bed pan into the space between said sections, when the latter are spread, beds of this nature being shown by my U. S. Patents Nos. 1,203,721 and 1,257,072.

One object of the present invention is to generally improve and simplify upon the construction previously used for elevating the pan, when the separable sections of the mattress support are spread.

In carrying out the above end, a carrier is provided for upward movement when the separable sections of the mattress support are separated, and a further object is to provide a unique form of bed pan rest mounted on said carrier and equipped with novel means for swinging it upwardly when the carrier nears its upward limit of movement, so as to conveniently position the bed pan for the patient's use.

With the foregoing and minor objects in view, the invention resides in the novel subject matter hereinafter described and claimed, the description being supplemented by the accompanying drawings.

Figure 1 is a plan view.

Figure 2 is substantially a central vertical longitudinal section, parts being in elevation, the bed pan and its supporting means being shown in elevated position.

Figure 3 is a side elevation showing the bed pan and its supporting means in their normally lowered positions.

Figure 4 is a top plan view of the bed pan supporting means.

Figure 5 is a sectional view on line 5-5 of Fig. 4.

Figure 6 is a disassembled perspective view of the bed pan supporting means.

Figure 7 is a top plan view of the bed pan.

Figure 8 is a side elevation thereof.

In the drawings above briefly described, the numeral 7 designates a mattress-supporting spring capable of use on practically any of the well-known types of beds such as those commonly used in hospitals, sanatoriums and the like, said spring being preferably of the link and spring construction shown, suitable means 7' being provided for stretching said spring from time to time, as occasion may require. Also, the spring 7 is preferably provided along its edges with hooks H, by means of which a sheet may be held in a stretched condition over the head and foot sections of a mattress M. The spring 7 includes a pair of transversely separable sections 8 carried within rectangular frames 9 which slide upon a main supporting frame 10 of elongated rectangular form, said frame being secured at its front and rear sides to the head and foot portions of the spring 7 so as to be supported principally thereby, being thus capable of movement with said spring as the latter yields under the movements of the patient.

The frame 10 is preferably in the form of a casting with its end bars 11 longitudinally depressed, and the side bars 12 of said frame are preferably of inverted T-shape in cross section, the frames 9 being slidably supported on the inner flanges of said bars 12, while the head and foot portions of the spring 7 are detachably connected to the outer flanges. By this arrangement, the entire frame 10 and all parts carried thereby may be removed when required for cleaning and sterilizing. The bars 11 are preferably supported by spring 11' resting on parts of the bed frame.

Extending transversely beneath the spring 7, immediately in rear of the frame 10, is an operating shaft 13 having suitable handles 14 in convenient reach of the patient. The shaft 13 carries a pair of beveled gears 15 meshing with similar gears 16 on short longitudinal shafts 17 which carry gears 18 meshing with rack bars 19 on the lower sides of the frames 9. The shaft 13 is mounted in bearings 20 carried by the rear side bar 12 of the frame 10, while other bearings 21 depend from said bar to rotatably support the shafts 17.

By the construction so far described, which is very similar to that disclosed in Patent 1,257,072, it will be seen that a forward push on either of the handles 14 will slide the

two frames 9 outwardly, whereas return of the handle to its initial position will similarly return said frames. When the frames are separated, a bed pan 22 is automatically elevated between them, by the construction described below.

A pair of parallel longitudinal bars 23 have been shown extending from the rear side bar 12 of the frame 10, to the head rail 24 of the spring 7, and extending between these bars, is a shaft 25 upon which a longitudinally disposed carrying arm 26 is pivoted, the free end of this arm being preferably forked as indicated at 27. Secured 15 by rivets or the like 28 upon the forked end 27, is a carrier plate 29 upon which the bed pan 22 normally rests, said plate preferably having a transverse rib 30 to engage the front side of the pan and prevent sliding 20 of the latter therefrom as will be clear by reference to Figs. 2, 3 and 6. The arm 26 passes over a preferably U-shaped crank 31 with which the shaft 13 is formed, and when said shaft is turned to spread the frames 25 9, said crank swings said arm upwardly, thus elevating the plate 29 and the bed pan 22. To more conveniently position this pan for use however, than would be possible if it always rested upon the plate 29, I provide 30 the construction described below.

A countersunk opening 32 is formed in the plate 29 and this opening receives a plate 33 upon which the bed pan rests, in addition to resting on the plate 29. In the 25 construction shown, plate 33 is formed with hinge knuckles 34 and a rod 35 connects these knuckles with the plate 29, said rod and knuckles being disposed at the edge of plate 33 remote from the pivoted end of arm 26. Fulcrumed between its ends on the rod 35, I have shown a lever 36, one end of which normally underlies the plate 33, while its other end 37 is in position to strike one bar 12 of the frame 10, when the bed 30 pan elevating means is swung upwardly as shown in Fig. 2. Thus, as the plate 29 nears the limit of its upward movement, the lever end 37 strikes the frame 10 and said lever is thus rocked upon its fulcrum, so that its inner end swings the rest 33 upwardly, during which movement, said rest swings the bed pan 22 upwardly from the supporting plate 29 and properly positions it within the then existing opening between the frames 9. When one of the handles 14 is operated to return the frames 9 to their initial positions, the bed pan 22 and its supporting means descend by gravity and the pan may then be easily removed for cleaning.

Preferably used in connection with the features above described, are two indicators 38 which are slidably supported in bearings 39 carried by the end bars 11 of the frame 10. These indicators have portions disposed

in the outward paths of the frames 9, so that outward movement of said frames will project said indicators. When the frames 9 return to their initial positions, the indicators are left projecting, giving notice to the 70 nurse or other attendant, that the bed pan has been used and should be emptied. These indicators are very similar to those shown by my U. S. Patent 1,203,721, the indicators of that patent being designated by the numbers 44 and 45. 75

It will be seen from the foregoing that a greatly simplified construction has been provided and that such construction will be very desirable and advantageous. Excellent 80 results may be obtained from the details disclosed and they may therefore be followed if desired, but within the scope of the invention as claimed, numerous modifications may be made. 85

I claim:

1. In combination, a mattress support including an open transverse frame between its head and foot portions and a pair of separable sections slidably carried by said frame, a normally lowered vertically swingable bed pan support pivoted under the mattress support on an axis transverse to the latter, a transverse shaft mounted under the mattress support at one side of said frame and spaced from the axis of said bed pan support, an operating handle for said shaft, operative connections between said shaft and said separable sections of the mattress support for sliding the latter in said frame, and a crank carried by said shaft and positioned to engage and raise said bed pan support when said shaft is turned to spread said separable sections of the mattress support. 95

2. In combination, a mattress support including an open transverse frame between its head and foot portions and a pair of separable sections slidably carried by said frame, a pair of laterally spaced bars projecting horizontally from one side of said frame toward the head of the mattress support, a longitudinally disposed vertically swingable arm pivoted at one end to and disposed between said bars, the other end of said arm being provided with a bed pan support disposed under said frame, a transverse operating shaft rotatably mounted at the side of said frame toward the head of the mattress support, said shaft having a cranked portion underlying said arm to effect upward swinging of the latter, and operating connections between said shaft and the aforesaid separable sections of the mattress support, for outwardly sliding said sections when said arm is swung upwardly. 115

3. In combination, a mattress support including an open transverse frame between its head and foot portions and a pair of separable sections slidably carried by said 120

frame, a longitudinally disposed carrying arm having a bed pan supporting plate at one end underlying the intermediate portion of said frame, means pivotally supporting the other end of said arm between said plate and the head of the mattress support, a transverse operating shaft operatively connected with said separable sections of the mattress support for operating the same, said shaft having a crank portion engaged with said arm to effect upward swinging of said arm and said plate, a bed pan rest in the form of a plate resting normally upon said supporting plate, means pivotally connecting said rest with said supporting plate supporting it on a transverse axis disposed at the edge of the rest toward the foot of the mattress support, and a lever fulcrumed between its ends at the end of said supporting plate remote from the pivot of the aforesaid arm, said lever having one end underlying said bed pan rest and having its other end adapted to strike the aforesaid frame as said supporting plate nears the limit of its upward movement.

4. In combination, a mattress support including an open transverse frame between its head and foot portions and a pair of separable sections slidably carried by said frame, a longitudinally disposed carrying arm having a bed pan supporting plate at one end underlying the intermediate portion

of said frame, means pivotally supporting the other end of said arm between said plate and the head of the mattress support, a transverse operating shaft operatively connected with said separable sections of the mattress support for operating the same, said shaft having a crank portion engaged with said arm to effect upward swinging of said arm and said plate, a bed pan rest in the form of a plate resting normally upon said supporting plate, means pivotally connecting said rest with said plate supporting it on a transverse axis disposed at the edge of the rest toward the foot of the mattress support, and a lever fulcrumed between its ends at the end of said supporting plate remote from the pivot of the aforesaid arm, said lever having one end underlying said bed pan rest and having its other end adapted to strike the aforesaid frame as said supporting plate nears the limit of its upward movement, whereby to operate said lever and swing said bed pan rest upwardly from said supporting plate.

In testimony whereof I have hereunto affixed my signature.

JOSEPH E. FAZAKERLEY.
